UNITED STATES PATENT OFFICE

WILLIAM H. GRENIER, OF ANTIGO, WISCONSIN.

HOIST.

Application filed November 15, 1926. Serial No. 148,534.

My invention relates to improvements in hoisting apparatus.

In accordance with my invention, I provide a portable hoisting apparatus, which is particularly well adapted for use in working upon railway locomotives, for removing parts therefrom and placing the same thereon. The hoisting apparatus may be manually operated and has a wide range of adjustment, whereby it may handle parts in portions of the locomotive which are ordinarily inaccessible. The apparatus is so constructed that the load may be carried at one side of the machine, without liability of the machine tipping over. I also provide means which is adjustable upon the running board of the locomotive, over which the extension mast may project, and having guide means for the cable, thereby preventing injury to the cable and running board.

Other objects and advantages of the invention will be apparent during the course of the following description.

In the accompanying drawings, forming a part of this specification, and in which like numerals are employed to designate like parts throughout the same,

Figure 1 is a side elevation of hoisting apparatus embodying my invention,

Figure 2 is a detailed longitudinal section through a portion of the extension boom,

Figure 3 is a side elevation of the apparatus showing the extension boom attached to the extension mast, and projected beyond the extension mast,

Figure 4 is an edge elevation of the apparatus,

Figure 5 is a plan view of the same,

Figure 6 is an elevation of the carriage of the apparatus, parts broken away, viewed from the opposite side to Figure 1,

Figure 7 is a longitudinal section through the extension mast,

Figure 8 is a horizontal section taken on line 8—8 of Figure 1,

Figure 9 is a plan view of an air cylinder engaging attachment,

Figure 10 is a side elevation of the same,

Figure 11 is a side elevation of a running board guard,

Figure 12 is a bottom plan view of the same,

Figure 13 is a horizontal section taken on line 13—13 of Figure 1, parts omitted, and,

Figure 14 is a transverse section taken on line 14—14 of Figure 3.

In the drawings, wherein for the purpose

of illustration, is shown a preferred embodiment of my invention, the numeral 15 designates a carriage frame, preferably tapered forwardly, as shown. The rear end of this frame is supported by wheels 16 carried by an axle 17, the ends of which are journaled in the ends of the frame 15. Near its forward end, the converging portions of the frame have connection with a transverse plate or web 18, welded or otherwise rigidly attached thereto which is pivotally mounted upon a forward transverse axle 19, the intermediate portion of which is preferably bent downwardly. This axle carries wheels 20, which may enter openings or notches 21, formed in the sides of the carriage frame 15, during the steering operation. The forward axle 19 is steered by means of a tongue 22, suitably secured thereto. The carriage frame 15 is longitudinally inclined and extends downwardly towards its reduced forward end. The extreme forward end of the carriage frame 15 is in the form of a socket having spaced parallel sides 23, as shown.

The numeral 24 designates the lower stationary element of an extension mast. The lower mast element 24 is tubular, and is preferably rectangular in cross section although it may be circular or in any other desired shape. The lower end of the mast section 24 is arranged within and between the sides 23 and is welded or rigidly attached thereto. Rigidly attached to the lower portion of the mast 24 are curved braces 25, diverging rearwardly for rigid attachment to the sides of the carriage frame 15, as shown. The mast section 24 is inclined toward the rear elevated end of the carriage frame.

Slidably within the mast section 24 is an upper mast section 26, in the form of a rack bar, having a longitudinal set of teeth 27. These teeth are adapted to be engaged by a gear or pinion 28, Figures 1 and 7, operating through a slot 29. This gear is carried by a transverse shaft 30 supported by plates 31, which are rigidly secured to the opposite sides of the mast section 24. The gear 28 is driven by a larger gear 28' engaged and driven by a smaller gear 32, which is rigidly mounted upon a shaft 33, turned by a handle or crank 34. The reverse turning movement of the gear 32 is prevented by means of a pawl and ratchet device 35.

In view of the foregoing description it will be seen that the upper mast section 26 may be raised or lowered by turning the handle

or crank 34, and may be locked in the adjusted position by manipulation of the pawl or dog 35.

The mast section 26 is provided at its upper end with a horizontal overhanging arm 36, preferably formed integral therewith. Mounted upon this arm to travel longitudinally thereof and to be projected beyond the same is an upper co-acting arm 37.

10 The arm 37 is provided with a pair of guide plates 38, rigidly attached to its rear end, and having a roller 39 mounted between them and suitably attached thereto. This roller engages the lower edge of the arm 36. The 15 arm 36 is provided at its rear end with a recess, within which is rotatably mounted a roller 39, projecting slightly above the upper arm 36 and supporting the arm 37. The arm 36 is provided with a pair of depending 20 plates 40, rigidly attached thereto and these plates are disposed upon opposite sides of the arm 36 and have notches 41, which receive the axle 42 of the roller 39, and limit the outward movement of the arm 37.

25 Rigidly attached to one plate 38 is a box 43, having a screw-threaded opening, for receiving a screw-threaded feed rod 44, the rear smooth end of which is rotatably mounted within a lug or ear 45, rigidly attached to the top of the mast section 26. Lugs 46 are rigidly attached to the rod 44, and operate upon opposite sides of the lug 45. The forward end of the screw-threaded rod 44 is square, for engagement with a suitable 30 wrench. It is thus seen that means are provided for shifting the arm 37 longitudinally with relation to the arm 36.

Suitably mounted within the forward end of the arm 37 is a sheave 47, engaging a cable 48, which is employed to raise and lower the object. The cable extends forwardly and passes over a guide sheave 49, mounted in a bracket 50, which is attached to the rear end of the arm 37. The cable extends forwardly 45 from this point and passes about a sheave 51, mounted in brackets 52, which are attached to the rear end of the arm 36. The cable 48 then extends downwardly, generally parallel with the mast sections 24 and 26 and passes about a guide sheave 52, mounted upon brackets 53, rigidly attached to the sheave section 24. The lower end of the cable is suitably attached to a drum 54, which is arranged between brackets 55, and rotatably 50 mounted thereon. The drum is rigidly attached to a shaft 56, and this shaft is turned by a large gear 57, driven by a smaller gear 58. This smaller gear is rigidly mounted upon a shaft 59, journaled in the brackets 53. 55 The shaft 59 may be turned by a crank 60 or the like, and the rotation of the shaft 59 in a reverse direction is controlled by suitable pawl and ratchet means 61.

60 I provide an extension-boom 62, for co-action with the adjustable arms 36 and 37,

and which is adapted to be projected a considerable distance beyond these arms. This boom comprises a tubular boom section 63 receiving a co-acting boom section 64, for 65 slide action therein. These boom sections 70 are preferably elliptical so that there is no tendency for them to turn with relation to each other. The boom section 63 is equipped with a housing 65, having a transverse shaft 66 journaled therein. This shaft has a gear 75 67 rigid thereon, operating through a slot 68, for engagement with teeth 69, formed upon the boom section 64. The gear 67 may be locked against rotation by a set screw 70 or the like. The shaft 66 is turned by means 80 of a crank 71 or the like. It is thus seen that the boom section 64 may be shifted longitudinally of the boom section 63, and when projected to the end of its travel, it will be a substantial distance in advance of the arm 37, 85 when such arm is projected to the end of its travel.

The inner end of the boom section 63 is slotted, providing a forked end and this forked end includes a pair of spaced fingers 90 72. This forked end is adapted for interlocking engagement with the forked end 73 of a coupling 74. The fingers 72 are provided at their forward ends with openings for receiving a bolt 75 also passing through an 95 opening 76 in the coupling 74. The free end of the coupling passes between spaced ears or knuckles 77, rigidly attached to the mast section 24, and these ears are apertured for receiving a bolt 78, passing through an opening 79 in the rear end of the coupling 74. 100

At its forward end, the boom section 64 carries a guide sheave 80. The boom sections are supported by a suspension element, such as a chain 81, which may be suitably adjustably secured to the boom section 63. This chain extends upwardly and is suitably attached to the arm 36. 105

It is sometimes desirable to suspend the boom 62 at an elevation above the lower mast section 24 and when this is to be done, the forked end of the boom section 63 is detached from the coupling 74, and this forked end is inserted upon the upper mast section 26, Figure 13. The end of the tubular boom section 63 interlocks with the teeth 27, while the fingers 72 extend upon opposite sides of the mast section 26. The bolt 75 is employed to connect the free ends of these fingers and a wedge 82 is preferably employed to be driven 110 between the bolt 75 and the edge of the mast section 26, thereby securely locking the boom section 63 with the teeth 27.

When it is desired to remove air cylinders or other round objects from the locomotive, the boom 62 may be removed from the hoisting mechanism, and the attachment shown in Figures 8 and 10 substituted therefor. This attachment embodies a shank 83, carrying outwardly diverging arms 84, the ends of 115 120 125 130

which are curved at 85, to receive the air cylinder. The arms 84 are connected by a transverse rod 86, having an intermediate loop, for engagement with a hook 88, carried by a cable 89 or the like. This cable may be suspended from the arm 36 or it may be passed to the drum 54, like the cable 48, whereby the attachment may be raised or lowered upon its pivot. The inner end of the shank 83 is preferably forked, as indicated at 90, for interlocking detachable engagement with the coupling 74, and is held thereto by the bolt 75 passing through the apertures 91. Any other suitable means may be employed for connecting the attachment with the mast section 24, or the mast section 26, as may be required, it being stated that the forked end 90 is adapted to be mounted upon the mast section 26 in a similar manner in which the forked end of the boom section 63 is mounted upon the mast section 26.

The numeral 92 designates a carriage or body portion of an adjustable guard, which is adapted for use in connection with my hoisting mechanism. The carriage 92 is adapted to be mounted upon the running board 93 of a locomotive and extends transversely of the running board, and is adapted to be shifted longitudinally of the running board. The carriage 92 is provided at its inner end with a depending extension 93', and at its outer end with a depending extension 94. The upper horizontal portion 92 of the carriage is supported by rollers 95, adapted to run upon the top of the running board 93 and the depending portion 94 is preferably equipped with vertical rollers 96, engaging the edge of the running board. The numeral 97 designates a sheave, arranged at the inner end of the carriage 92 and supported by a shaft 98. The shaft 98 is journaled in bearings 99, which are secured to the carriage 92.

The carriage 92 is adjusted longitudinally of the running board of the locomotive, to the desired point. After this is accomplished, the arm 37 may be arranged upon this carriage 92, to be more or less supported thereby. The cable 48, passing to the work to be raised or lowered, is trained by the sheave 97, and hence the cable and running board are both protected against unnecessary wear or injury.

The operation of the apparatus is as follows:

The mast section 26 may be first adjusted to the desired elevation, and the horizontal arm 37 may be projected outwardly to the desired position. The entire apparatus is portable and may be shifted in proximity to the locomotive, and the adjusted arm 37 extended into the space within the locomotive. The cable 48 may be attached to the part to be raised, such as a spring, and by rotating the drum 54, the part may be readily elevated. The apparatus may be employed to deliver

an object to the desired point of the locomotive. If it should be desired to raise an object at a greater distance than can be accomplished by projecting arm 37 to the extent of its movement, the boom 62 is employed. This arm may be mounted either upon the mast section 24 or upon the mast section 26, as may be required. The boom section 64 is now projected forwardly to the end of its travel and the cable passes over the sleeve 82, as clearly shown in Figure 3. When it is desired to remove air cylinders or the like, the boom may be removed from the machine and the cylinder manipulating attachment shown in Figures 9 and 10 employed, as explained.

It is to be understood that the forms of my invention, herewith shown and described, are to be taken as preferred examples of the same, and that various changes in the shape, size and arrangement of parts may be resorted to without departing from the spirit of my invention, or the scope of the subjoined claims.

Having thus described my invention, I claim:

1. In a portable hoisting apparatus, a wheeled frame, a mast mounted thereon, a substantially horizontal longitudinally adjustable arm device carried by the upper end of the mast and adapted to be projected outwardly therefrom, a longitudinally adjustable extension boom carried by the mast and adapted to be projected outwardly for a substantial distance beyond the outermost projected position of the arm device, means for supporting the extension boom from the arm device, a guide element carried by the free end of the boom, guide means carried by the arm device, a cable engaging the guide element and guide means, and a drum mounted upon the mast and having the cable attached thereto.

2. In a portable hoisting apparatus, a wheeled frame, a mast mounted thereon including a lower relative stationary tubular mast section, and an upper rack bar mast section slidable within the lower mast section and having a longitudinal set of teeth, operating means mounted upon the lower mast section engaging said teeth to longitudinally adjust the upper rack bar mast section, an overhanging arm device mounted upon the upper end of the rack bar mast section, a longitudinally extensible boom having its inner end forked to be mounted upon the rack bar mast section and to have interlocking engagement with the teeth thereof, means for supporting said boom, guide means carried by the overhanging arm device and boom, a drum mounted upon the lower mast section, and a cable engaging the guide means and attached to the drum.

3. In a portable hoisting apparatus, a wheeled frame, a vertically adjustable mast carried thereby, a longitudinally extensible

- overhanging arm device carried by the upper portion of the mast, guide means carried by the arm device, a wheeled carriage mounted upon the running board of the locomotive to be adjusted longitudinally thereof, a sheave mounted upon said carriage, a cable to engage said sheave and guide means, and a winding drum mounted upon the mast to engage the cable.
- 10 4. In a portable hoisting apparatus, a wheeled frame, a vertically adjustable mast carried thereby, a longitudinally extensible overhanging arm device carried by the upper portion of the mast, guide means carried by the arm device, a carriage adapted to be mounted upon the running board of a locomotive to be adjusted longitudinally thereof, said carriage being adapted to receive thereon and support the free end of the arm device, 15 a winding drum mounted upon the mast, and a cable to engage the guide means carried by the arm device and engaging the drum.
- 15 5. In a portable hoisting apparatus, a
- wheeled frame, a vertically adjustable mast carried thereby, a longitudinally extensible overhanging arm device carried by the upper portion of the mast, guide means carried by the arm device, a carriage mounted upon the running board of the locomotive to be adjusted longitudinally thereof, a sheave 20 mounted upon said carriage, a winding drum mounted upon the mast, and a cable engaging the guide means and the sheave and also engaging said drum.
- 20 6. In a portable hoisting apparatus, a 35 wheeled frame, a vertically adjustable mast carried thereby, an overhanging arm carried by the upper portion of the mast, guide means carried by said arm, a carriage mounted upon the running board of the locomotive to be adjusted longitudinally thereof, a sheave mounted upon said carriage, a cable to engage said sheave and guide means, and a winding mechanism connected with the cable.

In testimony whereof I affix my signature.

WILLIAM H. GRENIER.
